UNITED STATES PATENT OFFICE.

BRYAN P. JOYCE, OF DAVENPORT, IOWA.

TRAVELING LOCK FOR GUN CARRIAGES.

Application filed September 6, 1923. Serial No. 661,266.

(FILED UNDER THE ACT OF MARCH 3, 1883, 22 STAT. L., 625.)

To all whom it may concern:

Be it known that I, BRYAN P. JOYCE, a citizen of the United States, and a resident of Davenport, county of Scott, and State of Iowa, have invented an Improvement in Traveling Locks for Gun Carriages, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The present invention relates to traveling locks for gun carriages.

In the heavier type of mobile gun carriages it is necessary to retract the gun on its cradle in travel so as to relieve the carriage 20 of the unbalanced weight of the gun.

The principal object of the present invention then is to provide means for locking the gun in its retracted or traveling position.

Another object is the provision of such 25 means which may be readily moved from its locking position to a position out of the way when it is desired to fire the gun.

With the foregoing and other objects in view, my invention resides in the novel arrangement and combination of parts and in the details of construction hereinafter described and claimed, it being understood that changes in the precise embodiment of the invention herein disclosed may be made 30 within the scope of what is claimed without departing from the spirit of the invention.

A practical embodiment of the present invention is illustrated in the accompanying drawing in which

40 Fig. 1 is a partial plan view of the trail with the locking mechanism;

Fig. 2 is a front elevation of the locking mechanism; and

Fig. 3 is a section on the line A—A of

45 Fig. 2.

Referring to the drawing by numerals of reference:

I have shown a gun provided with a split 50 trail having trail members 4 and 5. Affixed to the trail member 4 at a point intermediate of its length is a U-shaped clip 6. Pivotally mounted on this clip by means of a bolt 8 is a supporting member 7 which carries the gun locking device. The clip 6 is

provided with undercut guide ways 9 to receive portions 10 of the supporting member 7 to guide said supporting member in its pivotal movement and also to prevent tipping of the supporting member. Mounted on the member 5 of the trail at a point 60 substantially opposite the clip 6 is another U-shaped clip 11. This clip is provided with a lug 12 grooved as at 13 to receive the free end of the supporting member 7 to retain this member in operative position. 65

When it is desired to fire the gun the supporting member is swung to inoperative position upon the trail member 4. When it is desired to lock the gun in its traveling position the supporting member is swung 70 to its operative position at an angle to this trail member with its end resting in the groove 13 of the lug 12.

The lug 12 at a point adjacent the groove is provided with a slot 14. Pivotally mounted on the supporting member near the end which is received in the groove 13 is a cam member 15 movable in the slot 14. This cam member is mounted on a shaft 16 journaled in the supporting member 7 and 80 detachably retained therein by means of a cotter pin 17. The cam member 15 is actuated by a crank 18 provided with a spring 85 pressed handle 19 carrying a plunger 20. A recess 21 in one side of the supporting member 7 is adapted to receive this plunger to hold the cam member in locking position. By means of this cam the supporting member 7 is securely fastened in its operative or 90 traveling position.

Means are provided on the supporting member to cooperate with the gun to retain the gun in traveling position. Various types of retaining means may be employed. The type I have found in practice preferable is 95 illustrated in the drawing and described below.

Intermediate its length and on its upper side the supporting member is provided with a socket formed as by guide ways 22. The 100 gun at its rear end is provided with a lug 23. Grooves 24 are formed in either side of this lug in such a manner that the lug may be readily slid into and between the guide ways 22 on the supporting member. This lug 23 105 on its under side is further provided with a recess 25 for a purpose which will herein-after appear.

A slot 26 is formed in the upper side of the supporting member between the guide ways 22 in a position to lie beneath the recess 25 in the traveling position of the gun. 5 Pivotaly mounted by means of a shaft 27 on the supporting member is a cam 28 adapted to move in the recess and slot formed in the lug and supporting member respectively. This cam is actuated by a 10 crank 29 provided with a spring pressed handle 30 carrying a plunger 31. On opposite sides of the shaft 27 and at points equi-distant therefrom the front wall of the supporting member is formed with recesses 15 32 and 33. These recesses are adapted to receive the plunger on the handle 30. By means of its handle the cam may be swung in the recess 25 and slot 26 so as to lock or release the lug from its seat between the 20 guide ways 22.

In traveling position the supporting member is first swung across the trails the gun is then retracted on its cradle until the grooves on the lugs pass between the guide 25 ways 22; the cam 28 is then moved into position where it will lock the lug between said guide ways. To prevent undue rearward movement of the lug in its guide ways the cam shaft 27 at its rear end is provided 30 with a circular head 34, this head lies against the rear side of the supporting member 7 and projects beyond the bottom of the guide ways 22 to contact with the lug and prevent undue rearward movement thereof.

35 Mounted on the member 4 and at a distance from the pivot 8 equal to the length of the supporting arm 7 is a plate 35; this plate is provided with a lug 36 formed with a groove in which is received the free end 40 of arm 7 when the same is moved to inoperative position for firing of the gun. A recess 37 is provided in the base of this lug adapted to receive the cam lock 15 for securing the supporting member in its inoperative or firing position.

The plate 35 may be riveted, bolted or otherwise secured to the trail member 4, and while I have attached it to this trail member at a position forward of the pivot 8 it is 50 obvious that it might as well be located rearwardly thereof.

As shown the lug is provided with grooves to slide in guide-ways in the supporting member. In practice any other type of connection might readily be employed, and it is obvious that for the cam locking means 55 15 and 28 any other suitable type of locking means might be substituted.

While in practice I have found it better 60 to provide the clips 6 and 11 as separate members of my invention these might as readily be made integral with the trail members.

I claim:

65 1. A traveling lock for gun carriages of the split trail type, including a supporting 130

member pivotally mounted on one trail member and adapted to be swung from inoperative position on said trail member to operative position at an angle thereto, means guiding said supporting member in its pivotal movement, a lug on the other trail member to receive the free end of said supporting member in operative position and a lug on the first mentioned trail member to receive 70 the free end of said supporting member in inoperative position, means cooperating with said lugs to lock said supporting member in either position, guide ways on said supporting member, a lug on the gun adapted to enter said guide ways when the gun is moved to traveling position, means to limit the movement of the gun in said guide ways, said gun lug provided with a recess, and a cam member pivotally mounted on said supporting member and adapted to enter said 75 recess for locking the gun in traveling position and means for maintaining said cam member in locked or unlocked position.

2. A traveling lock for gun carriages of 90 the split trail type, including a supporting member pivotally mounted on one trail member and adapted to be swung from inoperative position on said trail member to operative position at an angle thereto, a lug on the 95 other trail member to receive a portion of said supporting member in operative position, a lug on said first named trail member to receive a portion of said supporting member in inoperative position, means 100 cooperating with said lugs to lock said supporting member in either position, guide ways on said locking member, a lug on the gun adapted to enter said guide ways when the gun is moved to traveling position, said gun lug provided with a recess, a locking member mounted on said supporting member and adapted to enter said recess, and means to maintain said locking member 105 in locked or unlocked position.

110 3. A traveling lock for gun carriages of the split trail type, including a supporting member pivotally mounted on one trail member and adapted to be swung from inoperative position on said trail member to operative position at an angle thereto, a lug on the other trail member to receive a portion of said supporting member in operative position, a lug on said first named trail member to receive a portion of said locking member 115 in inoperative position, means to lock said supporting member in either position, guide ways on said supporting member, a lug on the gun adapted to enter said guide ways when the gun is moved to traveling position, said gun lug provided with a recess and a locking member mounted on said supporting member 120 and adapted to enter said recess.

4. A traveling lock for gun carriages of 125 the split trail type, including a supporting

member pivotally mounted on one trail member and adapted to be swung from inoperative position on said trail member to operative position at an angle thereto, a lug on the other trail member to receive a portion of said locking member in operative position, a lug on said first named trail member to receive a portion of said locking member in inoperative position, means to lock said supporting member in either position, a socket on said supporting member, a lug on the gun adapted to enter said socket when the gun is moved to traveling position, said gun lug provided with a recess and a locking member mounted on said supporting member and adapted to enter said recess.

5. A traveling lock for gun carriages of the split trail type, including a supporting member pivotally mounted on one trail member, and adapted to be swung from inoperative position on said trail member to operative position at an angle thereto, securing means on each trail member to maintain said supporting member in operative and inoperative positions, a socket on said supporting member, a lug on the gun adapted to enter said socket when the gun is moved to traveling position, said gun lug provided with a recess and a locking member mounted on said supporting member and adapted to enter said recess.

6. A traveling lock for gun carriages of the split trail type, including a supporting

member pivotally mounted on one trail member and adapted to be swung from inoperative position on said trail member to operative position at an angle thereto, a socket on said supporting member, a lug on the gun adapted to enter said socket when the gun is moved to traveling position said supporting member and lug being provided with aligned recesses and a cam member movable in said recesses and adapted to lock said lug in position.

7. A traveling lock for gun carriages of the split trail type, including a supporting member pivotally mounted on one trail member and adapted to be swung from inoperative position on said trail member to operative position at an angle thereto, a socket on said supporting member and a lug on the gun adapted to enter said socket, said supporting member and lug being formed with recesses, and means engaging in said recesses for locking said lug in said socket.

8. A traveling lock for gun carriages of the split trail type, including a supporting member adapted to extend from one trail member to the other, a socket on said supporting member, a lug on the gun adapted to enter said socket, said gun lug provided with a recess and locking means on said supporting member movable into said recess to lock said lug in said socket.

BRYAN P. JOYCE.
